CLAIM

The ornamental design for a removable vehicle armrest, as shown and described.

DESCRIPTION

FIG. 1 is an isometric view of a removable vehicle armrest showing my new design;

FIG. 2 is an end view thereof, with the opposite end view being a mirror image thereof;

FIG. 3 is a left side elevation view thereof;

FIG. 4 is a right side elevation view thereof;

FIG. 5 is a top view thereof; and,

FIG. 6 is a bottom view thereof.
